US00D835485S

(12) **United States Design Patent** (10) **Patent No.:** **US D835,485 S**
(45) **Date of Patent:** **** Dec. 11, 2018**

(54) **MULTIPLE GRIP AREA PLIERS**

(71) Applicant: **APEX BRANDS, INC.**, Apex, NC
(US)

(72) Inventors: **Tobias McKay Bridges**, Holly Springs, NC (US); **Jonathan Siebert Beckwith**, Charlotte, NC (US); **Randi Ligon**, Raleigh, NC (US); **John Griffin Biering, Jr.**, Raleigh, NC (US); **Zachary Grant Hays**, Belmont, NC (US); **Trent Kahute**, Atlanta, GA (US); **Alexander Troitzsch**, Atlanta, GA (US); **Stephanie Lewis**, Atlanta, GA (US); **Justin Arsenault**, Atlanta, GA (US); **Alan David Anderson**, Willow Springs, NC (US); **George R. Thompson, IV**, Fuquay Varina, NC (US)

(73) Assignee: **APEX BRANDS, INC.**, Apex, NC (US)

(**) Term: **15 Years**

(21) Appl. No.: **29/619,524**

(22) Filed: **Sep. 29, 2017**

Related U.S. Application Data

(63) Continuation of application No. 29/571,612, filed on Jul. 20, 2016, now Pat. No. Des. 801,770.

CLAIM

The ornamental design for a multiple grip area pliers, as shown and described.

DESCRIPTION

FIG. 1 is a perspective view of a multiple grip area pliers in accordance with an embodiment of the present invention; FIG. 2 is a top view of the multiple grip area pliers of FIG. 1;

FIG. 3 is a bottom view of the multiple grip area pliers of FIG. 1;

FIG. 4 is a left side view of the multiple grip area pliers of FIG. 1;

FIG. 5 is a right side view of the multiple grip area pliers of FIG. 1;

FIG. 6 is a front view of the multiple grip area pliers of FIG. 1; and,

FIG. 7 is a back view of the multiple grip area pliers of FIG. 1.

(Continued)

The broken lines illustrate portions of the multiple grip area pliers that form no part of the claimed design.

1 Claim, 5 Drawing Sheets
